[57] ABSTRACT

A hydraulic motor of the radial piston type character-

ized in the provision of a housing having a plurality of radially extending cylinders in which pistons are radially reciprocable, said pistons being linked to the crankpin of a crankshaft journaled in said housing, and being successively communicated by valve means operated in timed relation to the rotation of the crankshaft with inlet and outlet ports of said housing so that during the power stroke of each piston, a succeeding piston is simultaneously communicated with the inlet port so as to produce a toggle joint force at the crankpin to provide a motor having increased torque and efficiency. The hydraulic motor herein is further characterized in that it has at least three equally spaced apart radial pistons linked to the crankpin of the crankshaft whereby, during rotation of the crankshaft, toggle joints as aforesaid are successively defined by the crankpin and the connecting rods of the first and second pistons, the second and third pistons, and the third and first pistons. The hydraulic motor herein is still further characterized in that the toggle joint force aforesaid at the crankpin for driving the crankshaft is initiated prior to the trailing piston reaching its top dead center position at which time it is pressurized and is continued until the leading pressurized piston has passed its bottom dead center position at which time pressure thereon is released to the outlet port.

HYDRAULIC MOTOR

BACKGROUND OF THE INVENTION

Radial piston hydraulic motors generally comprise a cylinder block carrying pistons which are urged radially outwardly by fluid pressure into engagement with a surrounding stator thus to cause rotation of the cylinder block and its output shaft, the cylinder block being provided with a rotating valve member to alternately conduct fluid under pressure to the outwardly moving pistons and to exhaust fluid from the inwardly moving pistons. It is also known to provide a radial piston hydraulic motor in which the pistons are actuated radially inwardly, said pistons being connected to rocker arms having arcuate shoes engaged with a rotatable eccentric, and again, fluid flow into and from the radially outer ends of the cylinders is controlled by a rotating valve member.

SUMMARY OF THE INVENTION

In contradistinction to known types of radial piston hydraulic motors, the hydraulic motor herein comprises a housing having a plurality of radially reciprocable and linked to the crankpin of a single throw crankshaft journaled in said housing; and valve means operated in timed relation to the rotation of the crankshaft so that said pistons are successively communicated with inlet and outlet ports in the housing and so that, during the power stroke of each piston, a succeeding piston is simultaneously communicated with the inlet port to form a toggle joint in which a toggle force at the crankpin increases the motor torque and efficiency.

It is a principal object of this invention to provide a highly efficient radial piston hydraulic motor which is of simple construction for economy of manufacture and assembly.

It is another object of this invention to provide a radial piston hydraulic motor of the character indicated in which the toggle joint driving action on the crankpin of the motor crankshaft to which the pistons are linked commences prior to the trailing piston reaching its top dead center position and continues until the leading piston has passed its bottom dead center position.

Other objects and advantages will appear from the ensuing description.

BRIEF DESCRIPTION OF THE DRAWING

FIG. 1 is a central vertical cross-section view passing diametrically through the motor housing;

FIGS. 2, 3 and 4 are cross-section views taken along the lines 2—2 and 3—3, FIG. 1 and line 4—4, FIG. 3;

FIGS. 5 and 6 are typical displacement and torque curves of a hydraulic motor embodying the present invention; and

FIGS. 7 and 8 schematically illustrate the starting and finishing positions of the toggle joint action obtained by simultaneous pressurization of two successive pistons.

DETAILED DESCRIPTION OF A PREFERRED EMBODIMENT

The hydraulic motor 1 herein comprises housing parts 2 and 3 clamped together as by screws 4 and forming a crankcase having bearings 5:5 therein, such as the self-aligning spherical roller bearings shown in FIG. 1, for rotatably supporting the crankshaft 6 therein for rotation about its oppositely extending shaft portions 7 and 8 of which the shaft portion 7 extends

through the housing part 2 and bearing 5 to constitute the output shaft of the motor 1 and of which the shaft portion 8 extends through bearing 5 into a bore 9 of the housing part 3 and has affixed thereto a valve operating cam 10. The crankshaft 6 has thereon a counterweight 11 and a flywheel 12. A retainer plate 14 is bolted to the housing part 2 to retain a seal assembly 15 around the output shaft portion 7. A suitable mounting bracket 16 may be secured to the housing part as shown.

10 The housing part 2 is formed with three threaded openings 17 which are equally spaced circumferentially around the housing part 2 and which are axially offset with respect to each other as best shown in FIG. 1. Screwed into said openings 17 are the respective cylinder assemblies 18, each of which comprises an outer part 19 in which a piston 20 is reciprocable and an inner part 21 which has an enlarged bore 23 for radially slidably receiving a guide sleeve 24 which carries the wrist pin 25 to which the connecting rod 26 and piston

20 20 are connected as shown in FIGS. 1 and 2, the other ends of the connecting rods 26 being connected to the crankpin 27 of the crankpin 6 in side by side relation. The housing part 3 has a pressure inlet port 28 which communicates with an annular inlet chamber 29 which

25 is closed by a cover plate 30 which is secured to the housing part 3 as shown by the screws 31, said cover plate 30 also closing the bore 9. The housing part 3 also has a return port 32 adapted for communication with a fluid reservoir (not shown), said return port 32 having a passage 34 which opens into the cylindrical chamber 35 defined between the housing parts 2 and 3 so that the chamber 35 will be approximately one half full of hydraulic oil for lubricating the crankpin 27, the bearings 5, the cam 10, etc.

30 35 The housing part 3 also has a passage 36 therethrough which communicates with the chamber 35 above the return passage 34, said passage 36 intersecting the pressure inlet passage 28 and having therein a relief valve 37 to prevent build up of excess pressure in 40 the inlet passage 28, the outfall side of said relief valve 37 being communicated with the oil reservoir (not shown), and the spring biased relief valve member 38 having an opening therethrough for return flow to the reservoir in the event that the level of oil in the chamber 35 rises above the return passage 34. When the spring biased relief valve member 38 is moved away from its seat, the excess fluid pressure is relieved and conducted to the reservoir through the relief valve member 38 and to the return passage and port 34 and 50 32 via the chamber 35.

55 The housing part 3 has three equally spaced apart radially disposed bores 40 which intersect the annular pressure chamber 29 and the return chamber 41 within bore 9 in which the cam 10 is disposed, and in each radial bore 40 is a valve assembly 42 including a valve member 43 which constitutes a cam follower biased by spring 45 to maintain its cam follower bearing 46 in engagement with the surface of cam 10. The radially inner end of each valve member 43 is slotted as shown to straddle the opposite sides of the cam 10 to prevent rotation of the valve member 43 thus to maintain the surface of the cam follower bearing 46 parallel to the axis of the crankshaft 6. The valve member 43 is of 60 pressure balanced construction provided with a peripheral groove 47 which, when the respective valve members 43 are moved by the cam 10 radially outward as shown by the lower valve members 43 in FIG. 3, opens

communication between the pressure chamber 29 and the radially outer ends of the respective cylinder parts 19 by way of the conduit and fitting means 48 and which, when in the closed position as represented by the valve member 43 at the top in FIG. 3 opens communication between the outer end of the associated cylinder part 19 with the return chamber 41 via the conduit and fitting means 48 and the central bore 49 of the associated closed valve member 43.

In the illustrated embodiment of the hydraulic motor herein the pistons 20 are of one-half inch diameter and have a stroke of 3½ inches and the L/R ratio of the connecting rod length to the crankpin radius is about 3.1/1. In the operation of the hydraulic motor it is preferred to employ a pressure system having an accumulator therein to maintain a substantially constant inlet pressure to the motor 1 which together with the flywheel 12 are effective to provide average displacement and torque values as denoted by the lines 52 and 53 in FIGS. 5 and 6.

In the present case the surface of cam 10 is so formed that as the crankshaft 6 is driven in the direction indicated by the arrow in FIG. 3, each valve member 43 remains in open position for pressurizing its associated piston 20 for more than 180° rotation of the crankshaft 6 both prior to and after the respective top and bottom dead center positions of the crankpin 27 with respect to the associated piston 20, and hence, oil is displaced from each piston 20 during rotation to and from said dead center positions either through the open valve member 43 or through the associated check valve 51 which permits the thus displaced oil to flow to the pressure inlet chamber 29 in the event that the valve member 43 is in an intermediate position closing communication with both the inlet and return ports 28 and 32.

In the arrangement shown in single cam 10 operates all of the valve members 43 and by reason of the shaping of the cam surface of cam 10 as aforesaid, the pistons 20 are pressurized in sequence with two successive pistons 20 being operative to drive the crankshaft 6 with the assistance of a toggle force as clearly shown in FIGS. 7 and 8. FIG. 7 shows the connecting rods 26 of two successive pistons in their positions at the beginning of the toggle action as the trailing piston 20 at the top approaches its top dead center position, and FIG. 8 shows the same two connecting rods 26 in their positions at the end of the toggle action after the leading piston 20 at the left has passed its bottom dead center position.

As evident, when two successive pistons 20 are pressurized as shown in FIGS. 7 and 8, the connecting rods 26 and crankpin 27 form a toggle joint in which the toggle force $T = 2F' \cdot H/A$. In the specific embodiment of the invention herein shown and described the valve member 43 for the upper piston 20 is opened to inlet pressure when the crankpin 27 is about 23° in advance of its top dead center position (FIG. 7) and the valve member 43 for the left piston 20 pressurizes the latter until the crankpin 27 is about 35° past bottom dead center position (FIG. 8).

As the crankshaft 6 rotates from the FIG. 7 to the FIG. 8 position, the net torque in clockwise direction increases and decreases according to the relationship $\pm PB \mp F'C + TD$. Clockwise rotation of the crankshaft 6 beyond the FIG. 8 position operates the valve member 43 for the left piston 20 to communicate the same with the return port 32 and at the position of the crank-

pin 27 about 25° before the top dead center position with respect to the piston 20 at the right, the valve member 43 therefor is operated to close communication with the return port 32. At this stage there may be about a 2° rotation of the crankpin 27 before the right piston 20 is communicated with the inlet port 28, i.e. when the crankpin 27 is about 23° before the top dead center position with respect to the piston 20 at the right. Until that time the crankshaft 6 is driven by the top pressurized piston 20. When the top and right pistons 20 are thus pressurized the toggle action is repeated as already described in connection with FIGS. 7 and 8 whereby the top piston 20 becomes the leading (or left) piston 20 in FIG. 7 and the right piston 20 becomes the top trailing (top) piston 20 in FIG. 7. Finally, the left and right pistons 20 form a third toggle joint and as the rotation of the crankshaft 6 continues, the toggle joint action of FIGS. 7 and 8 is repeated.

The embodiments of the invention in which an exclusive property or privilege is claimed are defined as follows:

1. A hydraulic motor comprising a housing having inlet and outlet passages and having a plurality of radially extending cylinders; a crankshaft journaled in said housing having a crankpin; pistons reciproable in the respective cylinders and having connecting rods linking the respective pistons to said crankpin; valve means operated in timed relation to rotation of said crankshaft to successively communicate the radially outer end portion of each cylinder with said inlet and outlet passages with overlap of the communication of one cylinder and a succeeding cylinder with said inlet passage to produce a toggle force at said crankpin for increased motor torque and efficiency; said valve means communicating the radially outer end portion of one cylinder with said inlet passage prior to and after said crankpin reaches top dead center position thereof and communicates the radially outer end portion of a preceding cylinder with said inlet passage until said crankpin passes bottom dead center position thereof whereby a toggle force is imposed on said crankpin during the overlap of the communication of said one and preceding cylinders with said inlet passage.

2. The motor of claim 1 wherein said housing has at least three equally spaced apart cylinders with the pistons therein linked by the respective connecting rods to said crankpin; and wherein said valve means effects overlap as aforesaid of the communication of each cylinder and a succeeding cylinder with said inlet passage whereby successive toggle forces are produced at said crankpin during rotation of said crankshaft.

3. The motor of claim 1 wherein said valve means comprises valve members movable in said housing to selectively communicate said inlet and outlet passages with the respective cylinders; wherein a cam on said crankshaft actuates said valve members in sequence as aforesaid; wherein each valve member, in an intermediate position, closes communication of its cylinder with said outlet passage before communication is opened between said cylinder and said inlet passage while the piston therein is moving radially outwardly; and wherein a check valve between each cylinder and said inlet passage permits fluid flow from said cylinder to said inlet passage in such intermediate position of said valve member.

4. The hydraulic motor of claim 1 wherein each cylinder has a radially enlarged bore in which a guide sleeve of diameter greater than said piston is reciproable; said guide sleeve carrying a wristpin to which the radially inner end of the associated piston and the radially outer end of the associated connecting rod are connected.
